(57) **CLAIM**

(**) Term: **15 Years**

The ornamental design for an enclosure for a switch having sloping and convex curved top, as shown and described.

(21) Appl. No.: **29/530,781**

DESCRIPTION

(22) Filed: **Jun. 19, 2015**

FIG. 1 is a front perspective view of an enclosure for a switch having sloping and convex curved top according to the present disclosure;

(51) **LOC (10) Cl. 13-03**

FIG. 2 is a front view of the enclosure for a switch having sloping and convex curved top of FIG. 1;

(52) **U.S. Cl.**

FIG. 3 is a rear view of the enclosure for a switch having sloping and convex curved top of FIG. 1;

(53) **USPC .....** **D13/160**; D13/169

FIG. 4 is a first side view of the enclosure for a switch having sloping and convex curved top of FIG. 1;

(58) **Field of Classification Search**

FIG. 5 is a second, opposite side view of the enclosure for a switch having sloping and convex curved top of FIG. 1;

USPC D10/75, 96, 99, 100, 103; D13/110, 118,

FIG. 6 is a top view of the enclosure for a switch having

D13/123, 133, 154, 158-160, 169, 173,

sloping and convex curved top of FIGS. 1; and,

D13/177, 184, 199

FIG. 7 is a bottom view of the enclosure for a switch having

(Continued)

sloping and convex curved top of FIG. 1.
